ATTORNEY

UNITED STATES PATENT OFFICE

JOSEPH SOSS, OF ROSELLE, NEW JERSEY

METHOD OF MANUFACTURING HINGE BUTTS

Application filed May 16, 1930. Serial No. 452,859.

This invention relates to hinges and particularly to the method of manufacturing one of the butts of hinges and particularly to hinges of the covered joint type; and the object of the invention is to provide an improved method of fashioning from a bar of predetermined cross sectional form, a successive series of pairs of hinge butts, the butts of each pair being of the same general contour and form and in fashioning the bar through a series of forming operations in the production of each pair of hinge butts and finally severing said pairs of butts in forming independent and similar butt parts whereby strong and durable hinge butts will result; a further object being to provide a method of forming hinge butts wherein the bar stock is heated in advance of the successive forming operations to facilitate the proper formation of the pairs of butts and the resulting independent butts; a still further object being to provide a method of fashioning pairs of hinge butts having curved hood portions at one end thereof in such manner from the bar stock as to form the hood portions from the central portion of the fashioned part of the stock so that an equalized distribution and flow of the metal is provided during the successive forming operations, especially in shaping said hood portions whereby accurately shaped and perfectly formed pairs of butts may be produced; and with these and other objects in view, the invention consists in a method of forming hinge butts which is more fully hereinafter described and claimed.

The invention is fully disclosed in the following specification, of which the accompanying drawings form a part, in which the separate parts of my improvement are designated by suitable reference characters in each of the views, and in which:

Fig. 1 is a perspective view of two different forms of stock which I may employ in forming my improved hinge butts.

Fig. 2 is a plan view showing the first step of fashioning one end of the stock.

Fig. 3 shows the next step of fashioning the stock to partially form the pairs of hinge butts.

Fig. 4 is a bottom plan view of the stock formed in the manner indicated in Fig. 3.

Fig. 5 is a partial section on the line 5—5 of Fig. 4.

Fig. 6 is a view showing the method of completing the formation of one pair of butts.

Fig. 7 is a plan view of the pair of butts formed in the manner seen in Fig. 6, detached, indicating the removal of the joining fin or section.

Fig. 8 is a sectional view through the hood portion of one of the butts made according to my invention when completely formed, the section being on the line 8—8 of Fig. 9; and,

Fig. 9 is a section on the line 9—9 of Fig. 8.

In carrying my invention into effect, I provide relatively long bars or strips of material which may be of any desired cross sectional form, and in Fig. 1 of the drawings, I have shown at 10 a bar or strip of round stock and at 11 a bar or strip of oblong or rectangular stock, it being understood that any desired form of stock may be employed, depending upon the particular type of product to be formed. In practice, one end portion of the stock is heated to a temperature sufficient to facilitate the proper shaping of the material. The first step of my improved method consists in fashioning the stock to form an elongated and relatively thick blank body such as shown at 12 in Fig. 2 of the drawings, having arranged centrally of opposite side edges thereof laterally projecting extensions 13 which are arc-shaped or substantially V-shaped in form, the contour of these extensions varying in the different types of products formed. The body 12 and the extensions 13 remain intact with the bar which provides a means of feeding or handling the product in the further fashioning thereof.

The next step in my improved method consists in placing the body 12 as formed in Fig. 2 between forming dies 14 and 15 to fashion the same into the shape seen in Fig. 3, the ends 12a and 12b of the body 12 being angularly and laterally disposed, whereas the extensions 13 are drawn inwardly to form

walls or fillets between said angularly disposed ends and the crosshead 12c at opposite sides of the body 12.

The next step in forming the product consists in arranging the body 12 as formed in Figs. 3, 4 and 5 within and between forming dies 16 and 17, the operation of which will complete the general formation of the product to form a pair of hinge butts from the side portions 12a and 12b of the body 12, the crosshead 12c being depressed to form curved hood portions 18 arranged adjacent each other and joined by a connecting fin 20, and side walls for the curved hood portion which are seen at 21 in Fig. 8 of the drawings. It will be noted at this time that the thickness of the side walls 21 is somewhat greater than the thickness of the body parts and hood portions of the respective butts, thus providing strong and durable bearing members for the pintle pins of the hinge, said side walls being drilled to form the apertures 22 for the pintle pins, this completing the forming operation of the separate butts, it being understood that the connecting fin 20 is removed and the removal of this fin forms on each butt at the termination of the curved hood portions 18, stop shoulders or walls 19. It will also be apparent that the joining part of the stock as seen at 23 in Fig. 6 of the drawings is sheared off and removed after the formation of the pair of butt parts as seen in Fig. 6. The remaining end of the stock is then heated to form another pair of butts in accordance with the process above set forth, and this operation continues until the entire stock has been consumed, after which another bar or strip of stock is employed.

It will be apparent that by forming the hood portions from the central part of the workpiece disposed at the end of the bar in the manner set forth, and by utilizing dies having the wedge-shaped contour, tremendous power is available in the forming operation of the hood portions of the pair of butts, and this method of procedure also provides for the proper and easy flow of the metal during the shaping operations whereby the resulting products will be not only strong and durable but of a finished contour requiring no machine operations other than the possible removal of a flared metal which may prevail and the drilling or reaming of the pintle pin apertures in the side walls of the hood portion of the butts. By virtue of my improved process, a hinge butt of the type under consideration which is stronger according to comparative tests than any other butt of its kind, regardless of the method of its manufacture, can be manufactured and sold at a price at least equal to most hinge butts of this class and cheaper than the more expensive hinges.

It will be understood that while I have diagrammatically illustrated certain die

structures employed in forming pairs of hinge butts of specific contour, that my invention is not limited to the use of the specific arrangement of dies herein disclosed nor to the contour of the finished product or products and various other changes in and modifications of the method herein set forth may be made within the scope of the appended claims without departing from the spirit of my invention or sacrificing its advantages.

Having fully described my invention, what I claim as new and desire to secure by Letters Patent, is:

1. The herein described method of making pairs of hinge butts from bar stock which consists in first heating said stock, then fashioning the same to form a workpiece of predetermined contour, then fashioning the workpiece to form centrally thereof adjacently arranged curved hood portions joined by a connecting fin, and then removing said fin to form independent butt members.

2. The herein described method of making pairs of hinge butts from bar stock which consists in first heating said stock, then fashioning the same to form a workpiece having pairs of projecting members disposed centrally of opposite side edges of the workpiece, then fashioning the workpiece to form of that part thereof having the projecting members curved hood portions having side walls formed by said projecting members, said hood portions being connected by a coupling fin, and then removing said fin to form independent hinge butts.

3. The herein described method of making pairs of hinge butts from bar stock which consists in first heating said stock, then fashioning the same to form a workpiece having pairs of projecting members disposed centrally of opposite side edges of the workpiece, then fashioning the workpiece to form of that part thereof having the projecting members curved hood portions having side walls formed by said projecting members, said hood portions being connected by a coupling fin, then removing said fin to form independent hinge butts, and then forming pintle pin apertures in the side walls of the hood portions of said hinge butts.

4. The herein described method of making pairs of hinge butts from elongated bar stock which consists in heating one end portion of the stock, fashioning the heated end thereof to form a workpiece having pairs of projecting members disposed centrally of the opposite side edges thereof, then shaping the workpiece through a series of successive forming operations to form of the portions thereof having said projecting members, curved hood portions having side walls, and then severing the workpiece thus formed to form independent butt members.

5. The herein described method of making

pairs of hinge butts from elongated bar stock which consists in heating one end portion of the stock, fashioning the heated end thereof to form a workpiece having pairs of projecting members disposed centrally of the opposite side edges thereof, then shaping the workpiece through a series of successive forming operations to form of the portions thereof having said projecting members, curved hood portions having side walls, then severing the workpiece thus formed to form independent butt members, and forming pintle pin apertures in said side walls of the hinge butts.

6. The herein described method of making pairs of hinge butts from elongated bar stock which consists in heating one end portion of the stock, then fashioning the heated end thereof to form a workpiece having pairs of projecting members disposed centrally of the opposite side edges thereof and shank portions arranged at opposite ends of said workpiece, then fashioning the workpiece to arrange said shanks angularly with respect to each other and to arrange said projecting members substantially at right angles to the central portion of the workpiece and said shanks to form side walls, then fashioning the central portion of the blank and said walls to form curved hood members having side walls, the thickness of said walls being greater than that of the hood portion and shanks, and then removing that portion of the workpiece intermediate the hood portions to form independent butt members.

35 7. The herein described method of making pairs of hinge butts from elongated bar stock which consists in heating one end portion of the stock, then fashioning the heated end thereof to form a workpiece having pairs of projecting members disposed centrally of the opposite side edges thereof and shank portions arranged at opposite ends of said workpiece, then fashioning the workpiece to arrange said shanks angularly with respect to each other and to arrange said projecting members substantially at right angles to the central portion of the workpiece and said shanks to form side walls, then fashioning the central portion of the blank and said walls to form curved hood members having side walls, the thickness of said walls being greater than that of the hood portion and shanks, then removing that portion of the workpiece intermediate the hood portions to form independent butt members, and severing the butt members from said stock.

8. The herein described method of making pairs of hinge butts from elongated bar stock, which consists in heating one end portion of the stock, fashioning the heated end thereof to form a workpiece having pairs of projecting members disposed at opposite side edges thereof, then fashioning the workpiece to form of the portions thereof having the projecting members curved hood portions hav-

ing side walls, and then severing the blank thus formed to form independent butt members having the curved hood portions at one end thereof.

In testimony that I claim the foregoing as my invention I have signed my name this 9th day of May, 1930.

JOSEPH SOSS.
